ADJUSTABLE GUN SIGHT

Charles F. Lefever, Plymouth, Mich., assignor to
 Daisy Manufacturing Company, Plymouth,
 Mich., a corporation of Michigan

Application April 24, 1939, Serial No. 269,801

1 Claim. (Cl. 33—58)

The invention relates to adjustable sights for guns and consists in the novel construction and method of forming the same as hereinafter set forth.

5 In the drawing:

Figure 1 is a perspective view of a portion of the gun barrel to which my improved adjustable sight is to be secured and the adjustable sight detached therefrom;

10 Figure 2 is a longitudinal section through the barrel and sight attached to each other;

Figure 3 is a similar view showing the sight in elevated position;

15 Figure 4 is a cross section on line 4—4 of Figure 3;

Figure 5 is a plan view of the sight and barrel.

A is a gun barrel such for instance as the false barrel of a spring air gun. B is a rear sight member mounted on the top of the barrel A so as to be vertically adjustable in relation thereto. This sight member is formed preferably of a sheet metal stamping, which has integral therewith a shank member C extending forward of the barrel and with its forward end attached thereto, preferably by spot welding. This shank, therefore, forms a spring arm which permits of flexing to raise or lower the sight B. The means for effecting this raising and lowering of the sight comprises a screw D which has a threaded engagement with the shank C adjacent to the sight, said screw having a grooved head portion E for engaging a slot in the barrel A. As shown in Figure 1, the slot F in the barrel A is of a width less than the diameter of the head E, but sufficient to receive the core portion at the bottom of the groove in said head. One end of this slot is enlarged at F' sufficiently to receive the head E so that by moving the shank longitudinally of the barrel A the groove E' in the head E may be engaged with the sides of the groove F in the

barrel A. This permits of assembling the parts in the manner just described, after which the forward end of the shank C is spot welded to the barrel to hold the same in rigid relation thereto. The shank C is preferably formed with a reduced width portion C' intermediate the portion C² spot welded to the barrel and the remainder of the shank, said reduced width portion forming a spring tongue permitting the flexing of the shank. To facilitate assembly of the parts the barrel A is formed with a struck-out pintle G for engaging a corresponding recess H in the portion C², these parts engaging with each other after the grooved head E is properly engaged with the groove F of the barrel. Thus, the parts will be 15 properly positioned in relation to each other prior to the operation of spot welding.

With the construction as described the sight B may be raised or lowered by merely turning the screw D with a screw driver or other tool. The head E being swiveled in the barrel A, it is evident that the turning of the screw will lift or depress the portion of the shank having the threaded engagement therewith, this correspondingly moving the sight. The construction is one which 25 is exceedingly simple to manufacture and easily and accurately assembled.

What I claim as my invention is:

The combination of a gun barrel having a slot in the top portion thereof with an entrance aperture of greater width at one end of said slot, a sight provided with a shank for extending longitudinally of the barrel, a screw having a threaded engagement with said shank adjacent to said sight and provided with a grooved head engaged with said slot and adapted to be entered through said enlarged aperture, the end of said shank spaced from said sight and screw being welded to said barrel.
